URINE SPECIMEN RECEPTACLE OR SIMILAR ARTICLE

Louis Guss, 59 Achem St., Norwich, Conn.

Filed Aug. 7, 1962, Ser. No. 71,202

Term of patent 14 years

(Cl. D83—1)

FIGURE 1 is a top plan view of a urine specimen receptacle, or similar article, showing my new design;
FIGURE 2 is a side elevational view thereof;

FIGURE 3 is a vertical section, on the line 3—3 of FIGURE 1;

FIGURE 4 is an end elevational view as seen from the left of FIGURE 2;

FIGURE 5 is an end elevational view as seen from the right of FIGURE 2.

I claim:

The ornamental design for a urine specimen receptacle or similar article, as shown.
